CONTAINER WITH BOTTOM DISPENSING ROTOR

Alvah C. Roebuck, Jr., Tujunga, and Archie T. Arnold, La Crescenta, Calif.

Application August 6, 1948, Serial No. 42,957

12 Claims. (Cl. 222—339)

1

This invention relates to a mechanical device for translating motion and particularly to the application of such a device to dispensing apparatus. More specifically the invention relates to the translation of linear motion of one member into rotary motion of another and particularly into oscillating rotary motion to operate a dispenser, agitator, sifter, etc.

To accomplish this translation of motion, we provide mechanism comprising a rotatable member fixed with respect to linear motion, an elongated tongue extending co-axially through the rotatable member and fixed with respect to rotational motion, and means for causing linear motion of the tongue along the axis of rotation of the rotatable member to produce rotation of the rotatable member. These last named means generally comprise a co-axial bore in the rotatable member extending from one end thereof and opening at the opposite end through a slot which intersects the rotational axis of the rotatable member. A fixed member is mounted adjacent the said one end of the rotatable member and is provided with a slot therethrough which intersects a projection of the rotational axis of the rotatable member. The tongue is passed through the two slots and twisted about its longitudinal axis throughout a portion of its length traversing the slot in the rotatable member. Linear motion of the tongue in the direction of the axis of rotation of the rotatable member causes the first named slot to follow the twist in the tongue thereby rotating the rotatable member accordingly.

The tongue is stabilized against rotation at one end of the rotatable member by passage through the slot in the fixed member and at the opposite end by the means for imparting linear motion thereto. This means may be either manual or mechanical; particular mechanical means being described hereinafter.

A feature of the invention which lends it to diversified application is the ease by which the translated motion may be brought about by remote operation. Thus if the rotatable member is an agitator blade, dispensing device, etc. it will generally be disposed within a closed container comparatively inaccessible to manipulation. By extending the aforementioned tongue through a wall of the container the agitator, etc. can be rotated by externally produced linear displacement of the tongue.

A large field for application of the mechanism of the invention is in dispensing devices. In devices of this type, as for example sugar dispens-

2

ers, coffee dispensers, cream dispensers and the like, it is desirable to dispense at each operation a fixed and uniform quantity of material. The present invention is described with particular relation to its application in a coffee dispenser, but the same is equally applicable for dispensers for any granular or liquid material.

A dispenser in accordance with the invention comprises a container, a barrel rotatably mounted adjacent the bottom of the container. The barrel has a longitudinal hub through which a co-axial bore projects and an opening in the curvilinear wall thereof to receive from the container the material to be discharged. The container has an opening in the bottom thereof substantially closed by the barrel. A slot in one end of the barrel opens into the bore and intersects the rotational axis of the barrel. A slotted member is stationarily mounted adjacent the opposite end of the barrel with the slot therein intersecting a projection of the axis of rotation of the barrel. A semi-flexible tongue is inserted through the two slots, traversing the barrel bore, and extends through a side wall of the container in the slotted end of the barrel. The tongue is twisted throughout a portion of its length passing through the slot in the barrel. Linear motion of the twisted length of the tongue through the barrel slot causes the same to follow the contours of the tongue imparting rotation to the barrel, the direction of which is dependent upon the direction of linear travel of the tongue.

In a preferred form, the semi-flexible tongue extending through the side wall of the container is channelled on the inner side of a curvilinear handle and is anchored at its upper end to a lever pivotably mounted to the handle. By depression of the lever a linear motion is imparted to the tongue which as above described is translated into a rotary motion of the dispensing barrel. Conveniently, the tongue is spring loaded either within the barrel itself or otherwise so as to return the lever to the raised position and return the barrel to its so called rest position.

The angle of twist of the length of tongue passing through the barrel slot, together with the linear displacement of the tongue is conveniently such as to impart 120° of rotation to the barrel. The opening in the barrel wall defines an angle of approximately 120° with the center of rotation of the barrel. The opening in the container bottom defines an angle of approximately 60° with the axis of rotation of the barrel.

An opening from the container into the bar-

rel is conveniently formed in a flat plate superimposed above the barrel forming what may be termed a false bottom in the container. The only way for material in the container to pass through the false bottom and be discharged from the bottom of the container is by means of the rotating barrel.

The invention will be more clearly understood by reference to the following detailed description thereof taken in relation to the accompanying drawings in which:

Fig. 1 is a plan view of a dispenser in accordance with the invention;

Fig. 2 is a bottom view of the dispenser of Fig. 1;

Fig. 3 is a sectional elevation taken on the line 3—3 of Fig. 1;

Fig. 4 is a sectional elevation taken on the line 4—4 of Fig. 3;

Fig. 5 is also taken on the line 4—4 of Fig. 3 showing the dispenser mechanism in a different position;

Fig. 5A is a partial sectional view showing the incorporation of wiper blades in the barrel housing;

Fig. 6 is an exploded view of the dispensing mechanism;

Fig. 7 is a modification of the invention wherein the barrel may be rotated through one or more complete revolutions with each stroke of the tongue; and

Fig. 8 is a sectional elevation of the application of the invention to an agitator.

Referring to Figs. 1 to 6 it will be seen that the dispenser comprises a generally cylindrical container 10 having a handle 12 and a cover 13. The cover is conveniently molded of thin plastic cupped inwardly in its center section and provided with ribs 13A, 13B to impart rigidity thereto. The cover has a peripheral lip 14 which engages the container wall to hold the cover thereon.

The handle 12 is provided with upper and lower bosses 12A, 12B which are tapped to receive two screws 15, 15A which hold the handle to the container. The central portion 16A of the bottom 16 is embossed and is provided with a central rectangular opening 17. A barrel 18 is rotatably mounted in a block 20, the block being affixed to the embossed bottom 16A of the container by screws 21, 22 and to a false bottom 24 in the container by screws 25, 26. The barrel 18 which is conveniently made in two sections 18A, 18B has a hollow hub 28 forming a co-axial bore 29.

The block 20 is also conveniently made in two parts 20A and 20B. The two parts of the block 20 are joined along the vertical plane; Fig. 3 being taken through this plane.

The ends of the bore 29 are countersunk to receive tubular pivot bearings 32, 33 which extend outwardly from opposite ends of the barrel and are journaled in journal boxes 34, 35 in the block 20. The journal boxes are likewise countersunk to receive thrust bearings 36, 37 respectively. The bearing 32 has an enclosed end traversed by an elongated slit 32B which passes through the axis of rotation of the barrel. The opposite pivot bearing 33 is open ended; the associated thrust bearing 37 having a closed end likewise traversed by a slit 37B which passes through the axis of rotation of the barrel 18.

The two halves of the block 20 are held together by collars 40, 41 which are press fit over the journal boxes 34, 35 of the block.

A metal band or tongue 44 is passed through a wall of the container 10 and through the bore 29 in the barrel extending through the slit 32B in the pivot bearing 32 and the slit 37B in the thrust bearing 37. Throughout a portion 44A of its length adjacent the slit 32B in the pivot bearing the band 44 is twisted about its longitudinal axis through an angle of 180°. In one particular application of the invention the 180° twist extends over an inch and one half of the band length.

A helical spring 46 is disposed around the band within the barrel bore abutting at one end against the thrust bearing 37 and at the opposite end against the twisted length 44A of the tongue.

In a preferred embodiment a lever 50 is pivotably mounted at 52 to the handle 12 and projects through a slot 54 in the outer face of the handle. A finger tab 53 is conveniently formed or affixed on the projecting end of the lever. Depression of the tab 53 as viewed in Fig. 3 will cause linear displacement of the band 44 towards the left as it passes through the barrel 18.

Since the pivot bearing 32 is slotted at 32B and is free to rotate with the barrel 18 the linear displacement of the band 44 will cause the slot 32B to follow the contours of the twisted section 44A of the band. The angle of rotation of the barrel 18 will depend on the linear displacement of the band. In the example given above wherein the 180° twist was in an inch and one-half of the band length, one inch linear displacement of the band will impart 120° of rotation to the barrel 18. Displacement of tongue 44 to the left in the barrel will compress the spring 46 between bearing 37 and the twist in the tongue. When the finger tab 53 is released, the spring will return the tongue and lever 50 to the position shown in Fig. 3.

The linear displacement of the tongue or band 44 may be limited in a number of ways. In the particular embodiment illustrated the wall of the container will act as a stop. Alternatively, the end of the tongue can be reduced in width, as shown for example in Figs. 4 and 5, and the slot 37B can be dimensioned to pass the small end of the tongue but to prevent passage of the wider portion thereof. Also the slot 54 in the handle can be dimensioned so as to limit the stroke of the lever 50. Any of these expedients or others which appear feasible may be employed to establish the tongue travel.

Referring now to Figs. 4 and 5 it is seen that the barrel 18 has an opening 56 in a wall thereof. Similarly the bottom 16A of the container has an opening 17 and the false bottom 24 has an opening 58. The openings 17 and 58 are partially enclosed by the block 20. The block 20 has a bottom opening 59 centered in the opening 17 and a top opening 60 centered in the opening 58. The opening 56 in the barrel includes an angle of approximately 120° with the axis of rotation of the barrel and the openings 59, 60 in the block include an angle of approximately 60° with the axis of rotation of the barrel. By rotating the barrel through 120° the opening 56 is alternately aligned with the openings 60 and 59 in the block 20. Half of the opening 56 is aligned with the opening 60 and upon rotation through 120° the opposite half of the opening 56 is aligned with the opening 59 while the opening 60 is closed by the barrel wall.

Thus there can be no direct flow of material

from the container through the openings 60 and 59.

To dispense a measured quantity of material the finger tab 53 is depressed causing the barrel to rotate from the position in which the opening 56 is aligned with opening 60 to a position where the opening 56 is aligned with the bottom opening 59; the exact quantity being determined by the size of the barrel.

In many applications it is desirable to dispense a uniform and predetermined quantity of material. For example in making coffee it is convenient to dispense a heaping tablespoon of coffee for each cup. For this purpose the barrel is designed so as to hold exactly a heaping tablespoon of coffee. In this manner, upon each depression of the finger tab 53 a tablespoon of coffee grounds will be discharged. Smaller barrels may be used for sugar or the like or larger barrels may be constructed for other purposes.

If the dispenser is to be used for dispensing liquids it may be desirable to include a wiper seal in the block 20 so as to insure against leakage of the liquid between the barrel and the block. In Fig. 5A, the block and barrel are shown in partial sectional elevation. In this embodiment wiper seals 62, 63 are embedded in the wall of the block 20 so as to wipe against the barrel 18. The wipers are so positioned as to seal the barrel while in either the receiving or discharging position.

In the embodiment of Fig. 7 the barrel 70 is rotatably mounted in a block 72 which is in turn mounted within a container 74. The barrel 70 and the block 72 are substantially similar to the barrel and block heretofore described. A metal band or tongue 76 is passed through a bore in the barrel as in the foregoing embodiment. In the embodiment of Fig. 7 however, the band is provided with an elongated twisted section. In this case linear motion of the band 76 will cause rotation of the barrel 70 through one or more complete revolutions depending upon the linear displacement of the band. The number of revolutions which the barrel is rotated will be a function of the pitch of band twist and the linear displacement of the band. This application of the invention finds use in dispensers for example where multiple discharge is required from a single stroke.

Although the invention has been described with particular reference to its application in dispensers, it may be employed to advantage in other applications.

The embodiment shown in Fig. 8 illustrates the application of the invention to an agitator as for example in a storage bin, or the like. A block 80 is mounted within a bin or container 82 and supports an agitator 84 rotatable in the block. The agitator 84 is provided with a plurality of blades 85, 86, etc. A band 87 carried through a wall 82A of the bin and twisted throughout a portion of its length 87A is passed through a hub 84A of the agitator. Linear motion of the band 87 through the hub 84A induces rotation of the agitator 84 in the manner above described. Household use of such an agitator may be employed for flour sifting or the like. For commercial use the twisted band may be considerably larger and may be used in storage bins or the like for conventional purposes.

We claim:

1. A dispenser comprising a container, a barrel rotatably mounted adjacent the bottom of the container, the barrel having a hub and a co-

axial bore in the hub, an opening in the curvilinear wall of the barrel and an opening in the bottom of the container closed by the barrel, a first slit in an end of the barrel opening into the bore, a stationary member mounted adjacent the opposite end of the barrel and having a second slit therein, a tongue extending through the first slit, the bore of the barrel and the second slit, the tongue being twisted about its longitudinal axis throughout a portion of its length traversing the first slit, and means operable from the exterior of the container for moving said tongue linearly in the direction of the axis of rotation of the barrel.

2. A dispenser comprising a container having an opening in the bottom thereof, a housing mounted at the bottom of the container above the opening, a top and bottom opening in the housing, the bottom opening being aligned with the opening in the container bottom, a barrel rotatably mounted in the housing, the barrel having a hub and a co-axial bore in the hub, an opening in the curvilinear wall of the barrel, a first slit in an end of the barrel opening into the bore, a stationary member mounted adjacent the opposite end of the barrel and having a second slit therein, a tongue extending through the first slit, the bore of the barrel and the second slit, the tongue being twisted about its longitudinal axis throughout a portion of its length traversing the first slit, and means operable from the exterior of the container for moving said tongue linearly in the direction of the axis of rotation of the barrel to rotate the barrel so as to alternately align the opening therein with the top and bottom openings in the housing.

3. A dispenser according to claim 2 having a false bottom above the housing and an opening in the false bottom aligned with the top opening in the housing.

4. A dispenser comprising a container having an opening in the bottom thereof, a housing mounted in the bottom of the container above the opening and having a top and bottom opening therein, the housing having a journal box at each end thereof, a barrel rotatably mounted in the housing, the barrel having a hub, and a co-axial bore in the hub, a tubular bearing extending from each end of the bore and journaled in a journal box, an opening in the curvilinear wall of the barrel, a first slit in an end of one of the tubular bearings opening into the bore, a stationary member mounted adjacent the opposite end of the barrel and having a second slit therein, a tongue extending through the first slit, the bore of the barrel and the second slit, the tongue being twisted about its longitudinal axis throughout a portion of its length traversing the first slit, and means operable from the exterior of the container for moving said tongue linearly in the direction of the axis of rotation of the barrel.

5. A dispenser according to claim 4 wherein the housing comprises two separate identical parts joinable in a vertical plane passing through the longitudinal axis of the housing, the two parts being held together by a pair of sleeves disposed around said journal boxes.

6. A dispenser according to claim 4 wherein the means operable from the exterior of the container for moving said tongue comprises a lever rotatably mounted to the container and means affixing the outer end of the tongue to the lever.

7. A dispenser comprising a container, a barrel rotatably mounted adjacent the bottom of the container, the barrel having a hub and a co-axial

bore in the hub, an opening in the curvilinear wall of the barrel and an opening in the bottom of the container closed by the barrel, a first slit in an end of the barrel opening into the bore, a stationary member mounted adjacent the opposite end of the barrel and having a second slit therein, a tongue extending through the first slit, the bore of the barrel and the second slit, the tongue being twisted about its longitudinal axis throughout a portion of its length traversing the first slit, means operable from the exterior of the container for moving said tongue linearly in the direction of the axis of rotation of the barrel, and a helical spring disposed around the tongue between the stationary member and the twisted portion of the tongue.

8. A dispenser comprising a container, a barrel rotatably mounted adjacent the bottom of the container, the barrel having a hub and a co-axial bore in the hub, an opening in the curvilinear wall of the barrel and an opening in the bottom of the container closed by the barrel, a first slit in an end of the barrel opening into the bore, a stationary member mounted adjacent the opposite end of the barrel and having a second slit therein, a tongue extending through the first slit, the bore of the barrel and the second slit, the tongue being twisted about its longitudinal axis throughout a portion of its length traversing the first slit, a curvilinear handle mounted on the outside of the container, the tongue extending through a wall of the container and upwardly along the inside of the handle, and a lever pivotably mounted to the upper end of the handle, the tongue being affixed to the lever so that depression of the lever causes linear displacement of the tongue.

9. A dispenser comprising a container having a removable cover, a barrel rotatably mounted adjacent the bottom of the container, the barrel having a hub and a co-axial bore in the hub, an opening in the curvilinear wall of the barrel and an opening in the bottom of the container closed by the barrel, a first slit in an end of the barrel opening into the bore, a stationary member mounted adjacent the opposite end of the barrel and having a second slit therein, a tongue extending through the first slit, the bore of the barrel and the second slit, the tongue being twisted about its longitudinal axis throughout a portion of its length traversing the first slit, a handle mounted on the outside of the container, a lever pivotably mounted to the handle, the outer end of the tongue being affixed to the lever,

and a helical spring disposed around the tongue between the stationary member and the twisted portion of the tongue.

10. A dispenser according to claim 9 wherein the cover comprises a plastic member having an annular lip engageable with the sides of the container, the central portion of the cover being belled inwardly, and ribs extending across the belled section of the cover.

11. A dispenser according to claim 1 wherein the end of the tongue passing through the spring is narrower than the rest of the tongue and the spring is dimensioned so as to pass only the narrow end of the tongue and to limit travel by full compression of the spring.

12. A mechanical device for producing rotary motion comprising a stationary housing, a member rotatably mounted in said housing and having a coaxial bore, a slit in one end of the member intersecting the axis of rotation of the member and opening into the bore, a stabilizer stationarily mounted to the housing adjacent the opposite end of the rotatable member, a second slit in the stabilizer member intersecting a projection of the axis of rotation of the rotatable member, a lever arm pivotally mounted to the outside of the housing, an opening in the wall of the housing adjacent said one end of the rotatable member, and elongated flexible strip fastened at one end to said lever arm and extending through said opening, first slit, bore, and second slit, the strip being twisted about its longitudinal axis through a portion of its length in the region of the first slit and being flat on either side of said portion in the regions of the second slit and opening, and a helical spring mounted around the flat portion of the strip between the second slit and the twisted portion of the strip.
